Primary Examiner — Dana Meyrow(74) *Attorney, Agent, or Firm* — Pearl Cohen Zedek Latzer Baratz LLP(57) **CLAIM**

The ornamental design for a bottle, as shown and described.

DESCRIPTION

FIG. 1 is a front elevation view of the bottle;
 FIG. 2 is a back elevation view thereof;
 FIG. 3 is a right side elevation view thereof;
 FIG. 4 is a left side elevation view thereof;
 FIG. 5 is a bottom plan view thereof;
 FIG. 6 is a top plan view thereof;
 FIG. 7 is a top, front, right side perspective view thereof;
 and,
 FIG. 8 is a top, rear, left side perspective view thereof.
 The broken lines in the drawings illustrate the portions of the bottle that form no part of the claimed design.

1 Claim, 8 Drawing Sheets(56)
